ABRAHAM L. GAGE, OF PORTLAND, OREGON.

FLUME.

Application filed May 3, 1922. Serial No. 559,451.

My invention relates to metallic sectional flumes such as are used for irrigating purposes.

One of the main objects of my invention is to provide sections which are made of straight or flat sheets which are bent transversely to semicircular form, the abutting longitudinal ends of which overlap each other and the joints being sealed merely by the clamping action of transverse tension and compression members. By this means all sharp curves in the joints are eliminated and the galvanizing is not fractured and thus there is always a protecting covering over the sheet of metal. If the galvanizing on the plates is fractured corrosion sets up in a very short while and eats out the plates and it has been discovered that this is a serious objection to metallic flumes.

A further object is to provide a positive lock between the separate sheets and the clamping members so that there can be no relative motion and thus allow the clamping seal to be broken. This sometimes results from the flume assuming the catenary curve when the flume is partially filled with water and also by external force being applied to the clamping members which sometimes jars them loose and causes the seal to be broken.

A further object is to provide a compression member which is not recessed in the metal but in which the frictional resistance is materially eliminated by forming the same with round edges which do not interfere with the flow of water in the flume.

A further object is to provide the compression members with a slightly concaved under surface so that the compression member can pinch the sheets slightly but not sufficiently to flex the sheets and break the galvanizing.

A further object is to provide a novel clamping washer which forms a positive lock against longitudinal displacement and also functions to hold the compression member tightly against the sheets.

A further object is to provide a reinforcing shoe on the joints between the sections so as to substantially eliminate the loss of water thru the joint when the flume is distorted due to the pressure of the water carried by the flume.

These and other objects I have illustrated in the following drawings, in which:

Fig. 1 is a transverse section of my improved flume;

Fig. 2 is a fragmentary side elevation of the same;

Fig. 3 is a fragmentary longitudinal section taken on the line 3—3 of Fig. 1;

Fig. 4 is a view taken on the line 4—4 of Fig. 1 and shows an inside view of the joint of my flume;

Fig. 5 is a fragmentary section taken on the line 5—5 of Fig. 1;

Fig. 6 is a perspective view of the reinforcing shoe which is positioned on the joint of my improved construction;

Fig. 7 is a perspective view showing an alternative construction of this reinforcing shoe;

Fig. 8 is a partial transverse section of my flume and shows the positive clamping means for holding the plates and compressing members against relative movement;

Fig. 9 is a sectional view taken on the line 9—9 of Fig. 8 and shows a detail of construction;

Fig. 10 is a sectional view taken on the line 10—10 of Fig. 8 and shows one form of this clamping means for preventing relative displacement;

Fig. 11 is a diagrammatic representation of the form assumed by a flume due to the pressure of the water;

Fig. 12 is a fragmentary transverse section and shows an improved form of locking washer;

Figs. 13 and 14 are perspective views of the separate parts of this locking washer;

Fig. 15 is a section taken on the line 15—15 of Fig. 12.

The operation and construction is as follows:

My flume is made up of sections *a* which are flat sheets of galvanized plate which are rolled longitudinally to a semi-circular form. Abutting ends *a'* are lapped and are held between two clamping members, a tension member *b* and a compression member *c*. The ends *b'* of the tension member extend thru a cross bar *d* which supports the flume structure. A clamping washer *e* is mounted on the tension member *b* and the inner lip extends over the compression member *c* and the clamping action is increased by the tightening of the bolts *f* on the tension members *b*. A flat washer *g* is placed under the nut *f*. The clamping member *e* is made with a lip *e'* which extends inwardly beyond the

compression member and against which the compression member bears. The opposite end of the compression member e^2 is slightly longer than the inner lip e' and bears against the tension member b . It can be noted that tightening of the nut f will cause the lip e^2 to be moved inwardly and cause the lip e' to force the compression member downward and towards the tension member. As can be noted clearly in Fig. 5, the lips e' and e^2 are concaved slightly and the sides of the lip e' bear against the sheet a so as to encompass the compression member c and prevent it from slipping longitudinally. This will result in a tighter clamping action between the abutting ends. The compression member does not seat in any recess but is merely laid flat upon the surface of the inner sheet. It is made with curved edges and preferably is of half oval cross section so as to eliminate retardation to the passage of water. The compression member c is made with a slight recess c' underneath so that the force of the tension member tends to buckle the sheets slightly and cause them to pinch in this recess. This buckling effect is very slight and not enough to flex the plates sufficiently to flake off the galvanizing. This feature of my invention is of the utmost importance because any breaks in the protecting material however slight, causes a corrosion underneath which soon eats away a large section and causes leakage. Any beading or forming of the sections after they have been galvanized will cause this flaking and has been one of the serious objections to sheet metal flumes.

A shoe h is positioned on the bottom of the lapped end a' and forms a positive lock against displacement of the tension member b . It is formed with flanges h' in which are grooves h^2 in which the tension members rest. It can be seen that after the tension member is tightened the flange h' will prevent the tension member from being removed from the shoe and in ordinary circumstances the shoe h presents a broad surface which effectually locks the joint. In some cases it is desired to bolt thru the shoe and the lapped sections by means of bolts i and saddle strap j . This positively locks all members together. This shoe h may be made of corrugated metal as k and the tension member positioned in one of the longitudinal grooves and thus be prevented from slipping. This corrugated shoe performs a double function inasmuch as it more effectually stiffens the joint and substantially prevents the distortion of the sheet due to the weight of water carried by the flume.

The weight of water passing at its normal rate and normal volume causes the sheets to assume approximately the catenary curve as shown in Fig. 15 and for this reason I have provided means which will substan-

tially eliminate the gapping of the joints due to this effect. The stiffening plates at the joints will substantially eliminate bulging out below the line of the true semi-circle. Clamps l made up of inner members m and outer members n and held together by bolts o are positioned just above the water line of the flume and tend to draw the sheets outward and in constant contact with the tension member b . This clamp l does not hold the sheets in fixed relation but allows sliding action so that the pressure on the compression member will be allowed to fill out against the sheet at all times and thus effectually seal the joint between the lapped ends. I have provided a washer p which may be used in place of the washer e , which is made up preferably in sections as q and r . q is a section in which is a hole q' which corresponds in size to the tension member and which is mounted on the same. r is a member which has a slot r' which corresponds in size to the compression member and which is mounted therethru. The end of the compression member bears against the section q and the sides against the sides of the slot r' and thus the compression member is not allowed to move relatively to the tension member.

I claim:

1. In a flume, a plurality of semi-circular sections, the longitudinal ends of said sections overlapping each other, a transverse tension member encircling the exterior of said overlapping ends and a correspondingly arranged compression member bearing on the interiorly overlapping ends, these members adapted to clamp said overlying ends between them, means for applying said clamping force, a shoe curved approximately to the radius of the tension member, the latter bearing on said shoe, the shoe bearing against the overlying end section, said shoe being provided with means for holding the tension member in position on the shoe.

2. In a flume, a plurality of semi-circular sections, the longitudinal ends of said sections overlapping each other, a transverse tension member encircling the exterior of said overlapping ends and a correspondingly arranged compression member bearing on the interiorly overlapping ends, these members adapted to clamp said overlying ends between them, means for applying said clamping force, a shoe curved approximately to the radius of the tension member, the latter bearing on said shoe, the shoe bearing against the overlying end, said shoe being provided with means for holding the tension member in position on the shoe, a bolt extending thru said overlapped ends and said shoe to prevent the relative longitudinal displacement of the overlapped section ends.

3. In a flume, a plurality of semi-circular sections, the longitudinal ends of said sec-

tions overlapping each other, a transverse tension member encircling the exterior of said overlapping ends and a correspondingly arranged compression member bearing on the interiorly overlapping ends, these members adapted to clamp said overlying ends between them, means for applying said clamping force, a shoe consisting of an elongated plate, longitudinally corrugated and curved approximately to the radius of the tension member, the latter lying in said corrugation, the shoe bearing against the overlying end section, and other means holding the overlapped section ends against relative longitudinal displacement.

4. In a flume, a plurality of sections made of straight sheets bent transversely to semi-circular form, the longitudinal ends of said sections overlapping each other, a transverse tension member encircling the exterior of said overlapping ends and a correspondingly arranged compression member bearing on the interiorly overlapping ends, these members adapted to clamp said overlying ends between them, means for applying said clamping force, a shoe consisting of an elongated plate curved approximately to the radius of the tension member, the latter bearing on said shoe, the shoe bearing against the overlying end section, said shoe being provided with means for holding the tension member in position on the shoe.

5. In a flume, a plurality of sections made of straight sheets bent transversely to semi-circular form, the longitudinal ends of said sections overlapping each other, a transverse tension member encircling the exterior of said overlapping ends and a correspondingly arranged compression member bearing on the interiorly overlapping ends, these members adapted to clamp said overlying ends between them, means for applying said clamping force, a shoe consisting of an elongated plate, curved approximately to the radius of the tension member, the latter bearing on said shoe, the shoe bearing against the overlying end section, said shoe being provided with means for holding the tension member in position on the shoe, and other means holding the overlapped section ends against relative longitudinal displacement.

6. In a flume, a plurality of sections made of straight sheets bent transversely to semi-circular form, the longitudinal ends of said sections overlapping each other, a transverse tension member encircling the exterior of said overlapping ends and a correspondingly arranged compression member bearing on the interiorly overlapping ends, these members adapted to clamp said overlying ends between them, means for applying said clamping force, a shoe consisting of an elongated plate, longitudinally corrugated and curved approximately to the radius of the

tension member, the latter lying in said corrugation, the shoe bearing against the overlying end section.

7. In a flume, a plurality of sections made of straight sheets bent transversely to semi-circular form, the longitudinal ends of said sections overlapping each other, a transverse tension member encircling the exterior of said overlapping ends and a correspondingly arranged compression member bearing on the interiorly overlapping ends, these members adapted to clamp said overlying ends between them, means for applying said clamping force, a shoe consisting of an elongated plate, longitudinally corrugated and curved approximately to the radius of the tension member, the latter lying in said corrugation the shoe bearing against the overlying end section, and other means holding the overlapped section ends against relative longitudinal displacement.

8. In a flume, a plurality of semi-circular sections, the abutting longitudinal ends of which overlap each other, transverse tension and compression members clamping said overlying ends between them, said tension member being of circular cross section, said compression member being of elongate cross section, flume supporting means to which the ends of said tension members are secured, and washers under said trough supporting means, said washing members consisting of two pieces, one of which is provided with a slot to receive the adjacent end of the compression member, and having a recess at one side of such slot to receive the adjacent end of the tension member, and the other of said pieces having a hole for receiving said end of the tension member, the end of said compression member bearing against the second mentioned piece of the washer.

9. In a flume, a plurality of sections overlapping at their ends, each section being curved transversely to a semi-circular form, a transverse tension member encircling the exterior of said overlapping ends and a correspondingly arranged compression member bearing on the interior of said overlapping ends, these members adapted to clamp said overlapping ends between them, said sheets not being deformed in any other respect and being of sufficient thickness to resist any abrupt deformation due to the weight of the water which is imposed upon the flume when assembled, the inner face of the compression member being provided with a longitudinal groove, the overlapping ends of said sections extending beyond said compression member on each side of the latter and means for applying said clamping force.

10. In a flume, a plurality of sections overlapping at their ends, each section being curved transversely to a semi-circular

form, a transverse tension member encircling the exterior of said overlapping ends and a correspondingly arranged compression member bearing on the interior of said 5 overlapping ends, these members adapted to clamp said overlapping ends between them, the inner face of the compression member being provided with a longitudinal groove, the overlapping ends of said sections extending 10 beyond said compression member on each side of the latter, and means for applying said clamping force.

11. In a flume, a plurality of connecting semi-cylindrical sections, each of uniform 15 cross-section throughout its length, said sections being overlapped at their longitudinal ends, and means for securing said sections in place, comprising a transverse compression member arranged to bear on the interior 20 of said overlapped ends of said sections, a tension member arranged to bear on the exterior of said overlapped ends, and means independent of said sections adapted to engage the side edges of and thus hold 25 said compression members in place against shifting longitudinally of said flume.

12. In a flume, a plurality of connecting semi-cylindrical sections, each of uniform cross-section throughout its length, said sections being overlapped at their longitudinal ends, and means for securing said sections in place, comprising a transverse compression member arranged to bear on the interior 30 of said overlapped ends of said sections, a tension member arranged to bear on the exterior of said overlapped ends, and means independent of said sections secured on the 35

upper edges of said overlapped ends adapted to engage the side edges of and thus hold said compression members in place against 40 shifting longitudinally of said flume.

13. In a flume, a plurality of connecting semi-cylindrical sections, said sections being overlapped at their longitudinal ends, and means for securing said sections in place, 45 comprising a transverse compression member arranged to bear on the interior of said overlapped ends of said sections, a tension member arranged to bear on the exterior of said overlapped ends, and plates secured at 50 the upper edges of said overlapped ends, said plates provided with portions adapted to engage the side edges of and thus hold said compression members in place against shifting longitudinally of said flume. 55

14. In a flume, a plurality of connecting semi-cylindrical sections, said sections being overlapped at their longitudinal ends, and means for securing said sections in place, comprising a transverse compression member arranged to bear on the interior of said overlapped ends of said sections, a tension member arranged to bear on the exterior of said overlapped ends, and plates secured in 60 place on the upper edges of said overlapped ends, said plates provided, respectively, with a bent-over portion extending on the interior of said flume and recessed longitudinally of said compression member to embrace the latter and thus be adapted to engage its side edges to hold the same in place against shifting longitudinally of said flume. 65 70
